Rose Gaule Inventor

By *Lancaster and Allwine* Attorneys

UNITED STATES PATENT OFFICE.

ROSE GAULE, OF PEOSTA, IOWA.

DANCING DOLL.

Application filed April 25, 1921. Serial No. 464,125.

To all whom it may concern:

Be it known that I, ROSE GAULE, a citizen of the United States, residing at Peosta, in the county of Dubuque and State of Iowa, have invented certain new and useful Improvements in Dancing Dolls, of which the following is a specification.

This invention relates to toys of the type in which a suspended doll is made to dance by vibration and the objects of the present invention are, first to provide a novel means of constructing the doll so that an exceptionally simple, durable and inexpensive article will be formed, said doll construction permitting free movement of the limbs upon the vibration of the doll; second, to provide a novel means for mounting the doll so that the feet of the doll can be kept at a fixed relation to the platform; and third, to provide a novel means for actuating the doll or figure so that the figure can be readily operated.

With these and other objects in view, the invention consists in the novel construction, arrangement and formation of parts, as will be hereinafter more specifically described, claimed and illustrated in the accompanying drawings, forming a part of this specification, in which,

30 Figure 1 is a side elevation of the improved toy, parts of the supporting posts thereof being shown in section.

Figure 2 is a vertical section through the doll or dancing figure.

35 Figure 3 is a fragmentary vertical section taken at right angles to Figure 2 through the drawings illustrating the means of connecting the portions of the legs together and the legs to the body or trunk of the figure.

40 Figure 4 is a plan view of the figure illustrating the means of mounting the same on the supporting string and the means of actuating the figure, the neck of the figure being shown in section.

45 Figure 5 is a detail plan view of the dancing platform, the supporting post carried thereby being shown in section.

Referring to the drawings in detail, wherein similar reference characters designate corresponding parts throughout the several views, the letter A indicates the dancing figure or doll; B the platform therefor; C, the means for suspending the doll; and D, the actuating means for the doll or figure.

The dancing figure or doll A may be of any preferred character, that is, it may be dressed in any preferred manner. As shown the figure A includes the body or trunk portion 10, which may be made of wood if so desired. The upper portion of the trunk 10 is provided with an integral neck extension 11 on which the head 12 is adapted to be secured in any preferred manner. This head may be made of celluloid or any other suitable material. The trunk 10 has the arms 13 secured thereto, and these arms may be connected to the body in any preferred manner, either loosely or rigidly.

The lower end of the trunk 10 has connected thereto the legs 14, which includes the upper thigh sections 15 and the lower ankle sections 16. The lower ankle sections 16 have feet 17 formed thereon. The leg sections 15 and 16 are connected together 75 and to the trunk 10 in a novel manner which will be now described. This means renders the legs freely movable and forms an exceptionally durable and simple method of connecting the leg sections together and to the 80 trunk or body. As shown the lower portion of the trunk is provided with a pair of extensions 18 which are slotted as at 19. The meeting terminals of the leg sections 15 and 16 are also slotted as at 20 and 21. The 85 upper terminals of the leg portions 15 are also slotted as at 22. Suitable fabric strips 23 and 24 are utilized for connecting the legs to the trunk 10 and the leg sections together. The terminals of these fabric strips 90 23 and 24 are inserted in the slots 19, 22 and 20 and 21 respectively and may be secured therein by suitable adhesive or by threads or pieces of wire. It can be seen that these fabric strips allow a free movement of the 95 legs on the trunk and the leg sections in relation to each other. It is obvious that the fabric strips 23 and 24 may be connected to the trunk 10 and the leg sections in other ways, but I prefer to connect the same in the 100 manner shown in the drawings and just described.

The dancing platform B may be formed of wood or any other material and consists of the enlarged elliptical body portion 25 and 105 the reduced arms 26 and 27. These arms 26 and 27 support the end posts 28 and 29 respectively.

These posts 28 and 29 may be connected to the arms 26 and 27 in any preferred man- 110

ner, but as shown angle brackets 30 are utilized for this purpose.

The means C utilized for suspending the doll or dancing figure A above the dancing platform B comprises a longitudinally extending cord or string 31. This string or cord also can be formed of any preferred material, such as wire or fabric, and as shown the string extends through suitable openings 32 formed in the upper end of these posts and one end of the string is secured as at 33 to a suitable retaining member 34. The opposite end of the string is secured to a key 35, which is rotatably mounted in an opening 36. The opening 36 and the body portion 37 of the key are tapered so that a friction fit may be had between the walls of the opening and the outer surface of the body portion 37 of the key 35. It can be seen that by rotating the key 35 the tension of the string 31 may be adjusted and thus any slack occurring in the string may be readily taken up and the feet of the figure held at the required position in relation to the platform B.

The actuating means F for the dancing figure or doll A forms an important part of the invention and includes a frame 38, preferably formed of a single strand of wire. This frame includes the parallel arms 39 which have their terminals bent at right angles as at 40 and anchored in any preferred manner in the neck extension 11 of the trunk 10. The arms 39 continue rearwardly of the figure 10 and are bent to form eyes 41 which are adapted to snugly engage the string 31. Below the eyes 41 the frame 38 includes parallel leg portions 42 and these leg portions 42 terminate in a right angular extension 44 to which is secured a suitable finger piece 45.

In operation of the improved toy the forefinger is placed upon the finger piece 45 and a downward pressure exerted thereon. The forefinger is then quickly removed from the finger piece 45 and the string 31 will move the dancing figure A upwardly. This movement is rapidly continued and the figure will be alternately raised and lowered. This will cause the legs 14 and the leg sections 16 and 15 to swing or vibrate simulating a jiggling motion. By timing the tapping on the finger piece 45 and moving the finger to different points on the finger piece the figure or doll A can be made to describe various steps which will add to the interest of the toy.

If so desired the finger piece 45 may be suitably padded so as to form a cushion for

the fingers during the actuation of the toy. 60

From the foregoing description it can be seen that an exceptionally simple and durable toy has been provided which will be of interest to both young and old.

Changes in details may be made without departing from the spirit or scope of this invention; but,

I claim:

1. A dancing toy comprising a base, supporting posts carried by the base, a string 70 carried by the posts, a dancing figure mounted upon the string, and a finger piece carried by the figure and engaging the string at a point spaced from the figure.

2. A dancing toy comprising a base plate, supporting posts carried by the base plate, a string connected to the posts, a dancing figure connected with the string at its upper end, an actuating frame secured to the figure, means formed on the frame for engaging the string at a point spaced from the figure, and a finger piece formed on the frame at a point below the string. 75

3. A dancing toy comprising a base plate, 80 upstanding posts carried by the base plate, a string carried by the posts, a dancing figure connected at its upper portion to the string, an actuating frame for the figure including parallel arm portions, means anchoring the forward ends of the arm portions to the figure above the string, eyes formed on the arms for engaging the string, depending leg portions formed on the eyes, and a finger piece carried by the lower ends 85 of the leg portions. 90

4. A dancing toy comprising an elliptical base plate, outwardly extending arms formed on the opposite ends of the base plate, upstanding posts secured to said arms, the upper terminals of the posts having aligned 100 openings formed therein, a cord arranged through said openings, a dancing figure carried by the cord, means connecting one end of the cord to one of the posts, a rotatable key secured to the other post, and means 105 connecting the adjacent end of said cord to the key.

5. A figure comprising a body, a head, arms carried by the body, legs, the legs including a pair of sections, the meeting terminals of the leg sections having slots formed therein, the upper terminals of the upper leg sections having slots therein, the lower portion of the body having slots formed therein, and fabric strips arranged 110 in said slots connecting the legs to the body and the leg sections together. 115

ROSE GAULE.
